Primary Examiner — Karen E Eldridge Powers(74) *Attorney, Agent, or Firm* — Growling WLG (Canada) LLP; Joseph Conneely(57) **CLAIM**

The ornamental design for a pair of bra straps, as shown and described.

DESCRIPTION

FIG. 1 is a rear perspective view of a pair of bra straps according to the design;

FIG. 2 is another rear perspective view thereof;

FIG. 3 is a right side view thereof;

FIG. 4 is a rear view thereof; and,

FIG. 5 is a left side view thereof.

The broken line showing of the body of the bra in FIGS. 1-5 is for the purpose of illustrating portions of the environmental structure and forms no part of the claimed design. The broken line showing of the head, neck, arms, torso, and legs in FIGS. 1-5 is for the purpose of illustrating portions of the environmental structure and forms no part of the claimed design.
